Sweet Dolphin Muslin Hooded Baby Bath Towels—2 Pack 100% Cotton Towel for Babies, Infants, Toddlers—32x32Inch—Highly Absorbent and Newborn Essential, Light Bean Paste; Jun. 21, 2024; <https://www.amazon.com/SWEET-DOLPHIN-Muslin-Hooded-Towels/dp/B0D7QC1R35/?th=1>; 8Pgs. (Year: 2024).*

Primary Examiner — Michelle E. Wilson*Assistant Examiner* — Celse Moore, Jr.(57) **CLAIM**

The ornamental design for a swaddle towel, as shown and described.

DESCRIPTION

FIG. 1 is a front perspective view of a swaddle towel showing the claimed design;

FIG. 2 is a rear perspective view thereof;

FIG. 3 is a front view thereof showing a first side folded over;

FIG. 4 is a front view thereof showing a second side folded over;

FIG. 5 is a front view thereof showing a third side folded over;

FIG. 6 is a first side view thereof showing a fully folded state;

FIG. 7 is second side view thereof a fully folded state; and,

FIG. 8 is a rear view thereof a fully folded state.

Broken lines (if any) showing the environment in any figures are for illustrative purposes only and form no part of the claimed design.
